W. J. CALLOW.
FLUSH TANK CONTROL.
APPLICATION FILED MAY 2, 1917.

Patented Jan. 14, 1919.

1,290,905.

UNITED STATES PATENT OFFICE.

WILLIAM J. CALLOW, OF TORONTO, ONTARIO, CANADA.

FLUSH-TANK CONTROL.

1,290,905.

Specification of Letters Patent.

Patented Jan. 14, 1919.

Application filed May 2, 1917. Serial No. 165,922.

To all whom it may concern:

Be it known that I, WILLIAM JOHN CALLOW, a subject of the King of Great Britain, and resident of the city of Toronto, county of York, Province of Ontario, in the Dominion of Canada, have invented certain new and useful Improvements in Flush-Tank Controls, described in the following specification and illustrated in the accompanying drawings, that form part of the same.

The principal objects of the invention are to eliminate the undesirable prolonged noise made by the inflowing water to flush tanks following the flushing, and to obviate the unsatisfactory conditions of float valve controls.

A further object is to devise a simple compact and effective mechanism which will maintain a full flow of water to the tank until it is filled and will then cut off instantaneously.

The principal feature of the invention consists in the novel construction and arrangement of parts whereby an instantaneously closing valve is maintained full open for the maximum period and upon release closes quickly without causing a water hammer, the valve being retarded in closing by a water brake applied to the valve spindle.

In the accompanying drawings, Figure 1 is a perspective view of my improved control apparatus and Fig. 2 is a longitudinal elevational view shown partly in section.

In the practical application of the present invention the water supply pipe 1 extends into the tank and supports the self closing valve 2 which is of a well known type. The valve is arranged in a horizontal position with the spindle 3 extending toward the front wall 4 of the tank.

Secured upon the end of the valve spindle is an extension member 5 provided with a circular flange 6 which is formed with a ratchet notch 7. The outer end 8 of the extension member 5 is drilled transversely and a rod 9 is inserted therethrough and secured by the set screw 10. The rod 9 extends downwardly into the tank and has a sheet metal vane 11 secured to its lower end. The vane 11 is preferably bent into V shape and forms a brake to engage the water in the tank and retard the closing movement of the spindle against too rapid action, thereby preventing water hammer.

12 is a metal frame secured to the inner side of the front wall of the tank having a

sleeve 13 which extends through the wall and is secured at the outer side by a nut 14. The sleeve 13 is arranged in axial alinement with the spindle of the valve 2.

15 is a spindle journaled in the sleeve 13 having a suitable operating handle 16 secured to its outer end and upon its inner end is secured a cam plate 17 which is adapted on rotation to engage the lever 18 which is pivotally secured to the portion 19 of the frame 12.

The lever 18 is connected at its outer end 19 to a rod 20 for operating the release valve, which is not shown, and is guided in 70 its swinging movement by the slotted guide 21 on the frame 12.

The cam plate 17 is provided with a pair of pins 22 and 23 which project inwardly into the tank and extend each side of the 75 brake rod 9 and are so arranged as to engage the said rod upon the rotation of the cam plate to turn the spindle of the valve 2 coincident with the raising of the lever 18 to open the flush valve.

A pawl 24 is pivotally mounted on the stud 25 formed on the frame 12 and said pawl is formed with a hooked outer end 26 which rides upon the flange 6 carried on the spindle of the valve 2 and upon the rotation 85 of the said spindle to open the valve 2 the hook end 26 drops into the notch 7 and holds the valve full open.

A rod 27 is secured to the outer end of the pawl 24 and carries a ball float 28 at its 90 outer end.

In the operation of this device, upon the turning of the handle 16, the spindle 15 is rotated to open the inlet valve 2 through the connections described and the pawl 24 drops 95 into the notch in the flange 6 and holds the valve open. Coincidently with the opening of the valve 2, the lever 18 is raised to open the release valve. Upon the rotation of the spindle to open the valves the rod 9 100 is swung to a substantially horizontal position.

The water flows into the tank at full flow until it engages and lifts the float 28 thereby lifting the pawl to release the flange 6 whereupon the valve 2 immediately closes.

As the rod 9 and brake member 11 are rigidly connected to the valve spindle, the vane is forced downwardly in the water and checks the valve 2 against closing too rapidly.

A device such as described is extremely

simple and of a strong and durable nature and will not readily get out of order.

It will be noted that the cam 17 which lifts the lever 18 is free to return to its normal position following the action of opening the release valve and water valve so as to allow the lever to drop to its normal position and allow the proper closing of the release valve.

10. What I claim as my invention is:-

1. In a flush tank control, a valve for closing the water inlet having self-contained closing means, manually operated means for opening said valve, means for holding said valve open, a float connected to said holding means and adapted to release same, and means independent of the valve closing means for checking the closing movement of the valve.
2. In a flush tank control, a rotating self closing valve having a projecting spindle, a notched disk arranged on said spindle, a pivotal pawl resting on said disk and adapted to engage the notch therein to hold the valve open, a float secured to said pawl adapted to lift same clear of the notch, and means adapted to engage and rotate said spindle to open the valve.

3. In a flush tank control, a rotating self-closing valve having a projecting spindle extending horizontally, a rod secured to said spindle and extending downwardly therefrom, a vane secured to the lower end of said rod, a manually operated spindle adapted to be journaled in the side of the tank in alignment with the valve spindle, means secured to the inner end of said operating spindle adapted to engage said rod to rotate the valve spindle, means for holding the valve open, and float means for releasing said holding means.

4. In a flush tank control, a rotating self-closing valve having a projecting spindle extending horizontally, a rod secured transversely of said spindle, means for braking the rotation of the valve spindle carried by said rod, an operating handle having a spindle adapted to be journaled horizontally in the tank in alignment with the valve spindle, a member carried on the inner end of the operating spindle adapted to engage the transversely extending rod secured in the valve spindle, means for holding the valve open, and float means for releasing said holding means.

WM. J. CALLOW.
